UNITED STATES PATENT OFFICE

107,946

DESIGN FOR A SHOE

Warren L. Delaney, Auburn, Maine

Application April 17, 1937, Serial No. 68,849

Term of patent 14 years

To all whom it may concern:

Be it known that I, Warren L. Delaney, a citizen of the United States, residing at Auburn, Maine, have invented a new, original, and ornamental Design for Shoes, of which the following is a specification, reference being had to the accompanying drawing, forming part thereof.

Figure 1 is a side elevational view of a shoe showing my new design;

Figure 2 is a bottom plan view.

Figure 3 is a rear and side perspective view.

This design comprises a bulge on the inside shank of a shoe to provide a gracefully curved arch line which also gives the illusion of a high arch to the shoe.

I claim:

The ornamental design for a shoe, as shown and described.

WARREN L. DELANEY.
